HEIGHT MEASURING SCALE

Merwin Guy Hall, Rte. 1, P.O. Box 268,
Covington, La. 70433

Filed Nov. 1, 1971, Ser. No. 194,787

Term of patent 14 years

Int. Cl. D10—04

U.S. Cl. D52—6 A

FIG. 1 is a front elevational view of a height measuring scale showing my new design;

FIG. 2 is a left side elevational view thereof;

FIG. 3 is a top plan view thereof;

FIG. 4 is a front perspective view thereof.

I claim:

The ornamental design for a height measuring scale, as shown.
